UNITED STATES PATENT OFFICE.

ARTHUR DYMOCK, OF STOCKPORT, ENGLAND, ASSIGNOR TO AMERICAN CORETWINE COMPANY, OF BOSTON, MASSACHUSETTS, A CORPORATION OF MASSACHUSETTS.

MACHINE FOR THE MANUFACTURE OF PAPER TWINE.

1,241,943.

Specification of Letters Patent.

Patented Oct. 2, 1917.

Application filed June 11, 1914. Serial No. 844,564.

To all whom it may concern:

Be it known that I, ARTHUR DYMOCK, a subject of the King of Great Britain, residing at Stockport, in the county of Chester, England, have invented certain new and useful Improvements in Machines for the Manufacture of Paper Twine; and I do hereby declare the following to be a full, clear, and exact description of the invention, such as will enable others skilled in the art to which it appertains to make and use the same.

This invention relates to machines for the manufacture of paper twine from paper ribbon (or ribbons) which is twisted into twine in a damp or wet state by suitable means and which may have incorporated in it a hemp or the like twine.

The object of the said invention is to improve the appearance and increase the strength of such twine, to allow of the use of weaker paper than hitherto used in its manufacture, and to cheapen the means used for the said manufacture.

I attain this object by the machine illustrated in the accompanying drawings in which—

Figure 1 is a side view, and Fig. 2 a front view of a machine constructed in accordance with one embodiment of the said invention, Figs. 3, 4 and 5 are front views of details at an enlarged scale, Fig. 4 being sectional, and Fig. 6 is a detached side view of a machine constructed in accordance with an alternative embodiment of the said invention. Fig. 7 is a detached side view, Fig. 8 a detached front view, and Fig. 9 a detached plan of a machine constructed in accordance with the preferred embodiment of the said invention. Fig. 10 is a plan view showing the formation of the twine, with a core, which may be produced by my machine. Fig. 11 is a sectional view of the paper ribbon preparatory to its being twisted into twine, showing the preferred formation of the folds.

Similar letters refer to similar parts throughout the several views, and so on. According to one form of the improved machine and referring to Figs. 1 and 2, there are arranged on a frame in the known manner, a number of pairs of feed rollers *f* and *g* which may serve also as damping rollers, and a number of spindles *h* and

rollers *i* by means of which the paper twine is twisted and wound onto bobbins *j*.

There is secured to the machine a rectangular or similarly shaped bar *l* which may be composed of any suitable material, and is provided at intervals with a number of notches *m* (see Fig. 3). In front of the bar *l* are removably arranged a number of plates or blocks *n* each having a circular hole *o*. The plates or blocks *n* (see Fig. 5) may be made from pot, porcelain, metal or other suitable material and are provided with grooves so that they can be slipped onto or off their rods *p* at will, and there is one plate or block *n* for each pair of feed rollers *f* and *g*. The hole *o* is of suitable size to suit the width of paper ribbon *a* being dealt with, and a number of interchangeable plates or blocks *n* having holes of different sizes to suit the different widths of paper may be provided. In front of the plates or blocks *n* a number of grooved pulleys *q* are secured to a rotary shaft *r*. There are as many pulleys as there are pairs of feed rollers *f* and *g* and each pulley is provided with an annular groove *s* (see Fig. 80 4) having a flat bottom and preferably inclined sides.

When producing paper twine the paper ribbon *a* is drawn by the rotating pulley *q* under the bar *l* against which it presses and is thereby held flat (see Fig. 3). During its passage from said bar to the said plate or block *n*, the paper ribbon assumes under the influence of the said plate or block a U-shape, in cross-section, and so receives a central fold. The paper ribbon then passes through the circular hole *o* in said block when its passage into and through the said hole causes the paper ribbon to be again folded, and then through the groove *s*, which keeps the ribbon in its folded condition, the rotating pulley *q* giving in the well known manner the paper ribbon its twist and winding it onto the bobbin *j*. (Figs. 10 and 11).

When producing paper twine with a hemp or the like core, the core *e* is drawn under the bar *l*, through the hole *o* and the groove *s* with the paper ribbon, and engages in one of the notches *m* in the bar *l* which serve to hold the hemp or the like core central with the paper ribbon *a* (see Fig. 5) to prevent the said core from being twisted or bent.

Referring to Fig. 6, according to an alter-

native form of the improved machine where a slightly increased drag on the paper ribbon is of advantage or immaterial, the grooved pulleys may be dispensed with and in lieu thereof one or more open or closed eyes *b* may be provided to keep the paper ribbon *a* in its folded condition until twisted. The said eyes may be of any suitable material such as pot, porcelain, metal or the like.

According to the preferred form of the improved machine, also where a slightly increased drag is of advantage or immaterial, in lieu of the said grooved pulley there may be provided, see Figs. 7, 8 and 9, two guides *t* and *u* for each plate or block *n* and an eye *v*, the paper ribbon *a* passing over the guides *t* and *u* and through the eye *v* on its way to the bobbin *j*. The said guides and eye may be of any suitable material such as pot, porcelain, metal or the like. I preferably mount the plate or block *n*, the guides *t*, *u* and eye *v* on an oscillatable bracket *w* which may have means for readily securing it in position, so that they can be swung out of the way when the flier is to be removed. The eyes *b* shown in Fig. 6 may also be mounted on an oscillatable bracket as shown.

80. I claim:

1. In a machine for making twine of the character described, the combination of an element having a cylindrical hole, means for feeding a ribbon of suitable width through said hole in such a manner as to effect the continuance of a previously started double flat fold therein, with means for twisting the folded ribbon.

2. In a machine for making twine of the character described the combination of an element having a cylindrical hole therein adapted to continue a previously started double flat fold in the paper ribbon as it is fed through said hole, with means for twisting the folded ribbon.

3. A machine for making paper twine comprising, in combination, means for feeding the paper ribbon, means for moistening the paper ribbon as it is being fed, an element provided with a hole of suitable shape to abruptly continue at approximately the receiving end of the hole a previously started double flat fold in the paper ribbon as it is being fed therethrough, with means for twisting the folded ribbon.

4. In a machine for making paper twine the combination of means for moistening the paper ribbon, a bar having a longitudinally straight surface for frictionally engaging the top surface of the ribbon transversely thereof, an element provided with a hole, means for feeding the ribbon in engagement with said straight surface and through said hole, said means for feeding the ribbon, said straight surface and said

hole, so constructed and relatively arranged as to effect the abrupt continuance of a previously started double flat fold in the ribbon as it is being fed, with means for twisting the folded ribbon.

5. In a machine for the manufacture of paper twine from paper ribbon, a bar for keeping the paper ribbon flat, said bar having a slot for centrally positioning a core down on to the paper ribbon to the rear of the folding portion thereof, a plate in front of said bar having a hole for folding the paper ribbon around the fibrous core, a guide in front of the plate, and twisting means for twisting the paper ribbon after it leaves the guide.

6. In a machine for the manufacture of paper twine from paper ribbon, a bar secured to the frame of the machine for keeping the paper ribbon flat, a bracket oscillatably mounted on the frame of the machine in front of the bar, a plate removably secured to the bracket and having a hole for folding the paper ribbon, a guide secured on the bracket in front of the plate for keeping the paper ribbon in a folded state, and twisting means for twisting the paper ribbon after it leaves the guide.

7. In a machine for the manufacture of paper twine from paper ribbon, means for holding the fibrous core in the center of the paper ribbon, a bracket oscillatably mounted on the frame of the machine in front of said means, a plate borne by the bracket and having a hole for folding the paper ribbon, a guide in front of the plate for keeping the paper ribbon folded around the fibrous core, and twisting means for twisting the paper ribbon after it leaves the guide.

8. In a machine for the manufacture of paper twine from paper ribbon, a bar for keeping the paper ribbon flat, said bar having slots for holding the fibrous core in the center of the paper ribbon, a bracket oscillatably mounted on the frame of the machine in front of the bar, a plate borne by said bracket and having a hole for folding the paper ribbon around the fibrous core, a guide secured to the bracket in front of the plate for keeping the paper ribbon folded around the fibrous core, and twisting means for twisting the paper ribbon after it leaves the guide.

9. In a machine for making paper twine the combination of a bar having a longitudinally straight surface and a transverse slot therein; an element provided with a hole, means for feeding the ribbon in frictional engagement with said straight surface and through said hole, said means for feeding the ribbon, said straight surface and said hole, so constructed and relatively arranged as to effect the continuance of a previously started double flat fold in the ribbon as it is being fed, said slot in said bar

being for the purpose of bringing the core down on to the ribbon at a point back of the forming folds, with means for twisting the folded ribbon.

5 10. In a machine for making twine of the character described, the combination of an element having a substantially cylindrical hole therein, means for feeding a paper ribbon of suitable width through said hole in such a manner as to effect the continuance of previously started flat folds in the ribbon, which folds are formed by first folding the ribbon approximately in the center and refolding approximately in the center of the 15 first fold, with means for twisting the folded ribbon.

11. In a machine for the manufacture of paper twine from paper ribbon, a bar removably secured, for keeping the paper ribbon flat, said bar having a slot for centrally positioning a core down on to the paper ribbon to the rear of the folding portion thereof, a plate removably secured in front of the bar and having a hole, for folding 20 the paper ribbon around the fibrous core, guides secured in front of the plate for keeping the paper ribbon folded around the fibrous core, an eye secured to the front of the machine for guiding the paper ribbon 25 and fibrous core and twisting means for twisting the paper ribbon after it leaves the guides, for the hereinbefore specified purpose.

12. In a machine for the manufacture of paper twine from paper ribbon, a bar removably secured to the frame of the machine, for keeping the paper ribbon flat, a bracket oscillatably mounted on a horizontal part of the frame of the machine in front 30 of the bar to allow of being swung out of the way, a plate removably secured to the bracket and having a hole for folding the paper ribbon, guides secured in front of the plate to the bracket for keeping the paper 35 ribbon in a folded state, an eye secured to the

front of the bracket for guiding the paper ribbon and twisting means on the frame of the machine for twisting the paper ribbon after it leaves the guides, for the hereinbefore specified purpose. 50

13. In a machine for making paper twine, the combination of a folding device, means for feeding the paper ribbon therethrough in such a manner as to continue the previously started flat folds in the ribbon, which 55 folds are formed by first folding the ribbon approximately in the center and refolding approximately in the center of the first fold, with means for twisting the folded ribbon.

14. In a machine for the manufacture of paper twine, the combination of an element provided with a substantially cylindrical hole for making double flat folds in the paper ribbon as it is fed therethrough, with means for twisting the folded ribbon. 60 65

15. In a machine of the character described the combination of means for moistening the paper ribbon, means in front of said moistening means for keeping said ribbon flat, an element in front of said flattening means having a cylindrical hole therein for folding the paper ribbon in a double flat fold, and means for twisting the folded ribbon. 70 75

16. In a machine for making paper twine comprising, in combination, means for feeding the paper ribbon, means for moistening the paper ribbon as it is being fed, an element provided with a hole of suitable shape to abruptly continue a previously started 80 double flat fold in the paper ribbon as it is being fed therethrough, with means for twisting the folded ribbon.

In testimony whereof I have affixed my signature in presence of two witnesses.

ARTHUR DYMOCK.
